HIGH SPEED SCANNING SLOT ANTENNA FEED BY VARIABLE DELAY WAVEGUIDE HAVING HINGED OSCILLATED VANE

Ray G. Shankweiler, Cranbury, and Richard J. Klensch, Trenton, N.J., assignors to the United States of America as represented by the Secretary of the Air Force

Filed June 30, 1960, Ser. No. 40,124
2 Claims. (Cl. 343—768)

The invention relates to a hinge antenna for high speed scanning which is compact enough for incorporation in the wing of an aircraft.

Angular scan is accomplished in an antenna array by changing the relative phase between the radiating elements of the array. In a waveguide antenna array the procedure that is used to change the phase difference between adjacent elements is to change the phase velocity of the wave inside the guide. There are several ways that this can be done: first, changing the operating frequency or frequency scan; second, changing the permeability of the interior, for example, filling the waveguide with ferrite and varying the magnetic field; third, changing the field strength of the wave, and fourth, changing the waveguide geometry or mechanical scan. The present invention concerns an improved mechanical scan structure.

The prior art structure for obtaining high speed scanning of an antenna by mechanical means involves the movement of the entire back side of the waveguide that is opposite the aperture. This structure has numerous disadvantages, the principal ones being that a large mass must be moved and the waveguide structure is made weaker by having two longitudinal cuts made the length of the array.

It is thus an object of this invention to provide a hinge antenna for high speed scanning which has high resolution and is simple in construction.

It is a further object of this invention to provide an improved means for varying the waveguide geometry of an antenna for obtaining high speed scanning.

It is a still further object of this invention to provide a hinge antenna for high speed scanning which includes a waveguide having feed and load ends, an elongated aperture in one side of the waveguide, and a vane pivotally mounted within the waveguide extending along the length of the aperture and spaced therefrom.

The nature of the invention, further objects and advantages will appear more fully on consideration of the embodiments illustrated in the accompanying drawings.

In the drawings:

FIG. 1 is an illustration of the end view of one embodiment of the invention taken along 2—2 of FIG. 2;

FIG. 2 is an illustration of the top view of the FIG. 1 embodiment and includes the typical pattern for the antenna;

FIG. 3 is a perspective view of the waveguide portion of the novel antenna minus the vane element; and

FIG. 4 is a graphical representation of the effect that the vane angle makes on the antenna scan angle.

Referring now more particularly to FIGS. 1, 2 and 3, a hollow waveguide 10 of square cross-section has a feed end 12 and a load end 14. An elongated aperture 16 adapted to radiate extends lengthwise along one side of the waveguide 10. The waveguide has a suitable inner diameter to permit propagation of the TM_{1,1} mode. Metallic extensions 18 and 20 of length slightly longer than aperture 16 are bonded to the side of the wave-

2

guide containing the aperture to form a ground plane 22 on the aperture side of the waveguide. High speed scanning is accomplished by a drive means 24 driving a vane 26 back and forth within the waveguide between the extremes A and B. The vane 26 is pivotally connected to the waveguide by means of a piano hinge means 30.

The specific structure of drive means could be various types; however, it has been known that connecting the upper portion of the vane 26 to a motor-driven cam actuated push rod provides an excellent drive. The cam is shaped to produce a saw-tooth type scan.

Energy is propagated through the waveguide 10 from the feed end 12 toward the vane 26. When the vane is vertical in position C, the phase velocity is maximum (for a symmetrical field within the waveguide) and for a continuous radiator a beam near broadside would be expected. The presence of the aperture 16 on one side of the waveguide no longer keeps the field inside the waveguide symmetrical about the center of the guide. For this reason, maximum phase velocity occurs when the vane 26 is in the B position and the minimum phase velocity occurs when the vane 26 is in the A position.

FIG. 4 illustrates the deviation from the symmetrical field case that the novel antenna takes in the relationship 25 of the vane position to the scan angle θ of beam 32. The solid curve represents the symmetrical field case. The dashed curve represents the experimental findings from the testing of a model of the novel antenna. The model was constructed of 1.4 inch square waveguide with a 30 pivotal vane of $1/16$ inch aluminum sheet inserted 1 inch into the waveguide and a 38 inch aperture length. The included angle between positions A and B was 60° . This continuous slot traveling wave antenna was excited in the TM_{1,1} mode and operated at a frequency of 9.1 kmc. 35 With the vane in position A, the beam 32 was at an angle of 32° from broadside. In position B, the beam 32 was 12° from broadside.

Although but a single embodiment of the invention has been shown and described, it will be apparent to 40 those skilled in the art that many other forms thereof, as well as changes in that described, are possible. Having thus described the invention as a particularly simple system for high speed scanning, we claim:

1. A hinge antenna for high speed scanning, said antenna comprising: a waveguide having feed and load ends, and an elongated aperture in one side of said waveguide; an elongated vane; piano hinge means attached to said waveguide and said vane for pivotally mounting said vane within said waveguide extending along the length of said aperture; and means for driving said vane back and forth to produce said scanning.

2. A hinge antenna for high speed scanning, said antenna comprising: a waveguide of square cross-section having feed and load ends, and an elongated aperture 55 adapted to radiate in one side of said waveguide; metallic extensions bonded to the said side of the waveguide containing the aperture forming a ground plane on the aperture side of the said waveguide; an elongated vane; piano hinge means attached to said waveguide and said vane 60 for pivotally mounting said vane within said waveguide extending along the length of said aperture; and means for driving said vane back and forth to produce said scanning.
